PARCEL BAG

Robert M. Lackey, Cohoes, N. Y.

Application September 13, 1933, Serial No. 689,173

2 Claims. (Cl. 229—68)

Among the principal objects which the present invention has in view are: To provide a serviceable closure lock for paper bags mostly used by women when shopping; to facilitate the operation of closing such bags in service; and to reinforce the handle feature of the construction.

Drawings

Figure 1 is an extended view of the fragment 10 of paper or strip of which these bags are manufactured showing the complementary structural features which avoids any waste of material in separating the paper strip into bag elements, the broken lines shown in the drawings being used to 15 indicate score or bend lines for folding into envelope shape.

Figure 2 is a detailed view on enlarged scale 20 showing in detail the structure forming the major portion of the handle portion of the bag.

Figure 3 is a detailed view on enlarged scale 25 showing a fragment of the bag, the parts being arranged as the result of the first step in closing a bag.

Figure 4 is a detailed view showing the parts 30 of the lock disposed as in Figure 3, the section being taken on the line 4—4 in Figure 3.

Figure 5 is a detailed view on enlarged scale 35 showing the handle features in the closed position of the bag.

Figure 6 is a sectional view showing the arrangement of the parts when disposed as shown 40 in Figure 5, the section being taken on the line 6—6 in Figure 5.

Description

One of the main objects sought in the present 45 invention is that of preventing the accidental opening of bags, or the separation of the front 9 from the back 10, of the character herein set forth, when filled. It has been found that the goods or articles disposed in the bag exert a lateral or side pressure on the sides of the bag which succeeds in separating the same at the flap opening of the bag. It is to restrain this action that the blanks such as shown in Figure 1 are provided 50 at the one end with a slit 11 and at the other end with a tongue 12. The slit 11 is coincident with the folding line of the cover flap 13. The folding line in the drawings in Figure 1 is indicated in dotted lines and by the numeral 14.

When the bag is closed, the operator first inserts the tongue 12 through the slit 11, as seen best in Figures 3 and 4 of the drawings. The next step in the operation of closing the bag is to fold 55 the flap 13 down into closed position, bending

the same on the folding line 14, which as explained, is coincident with the slit 11.

It will be noted that the closure flap 13 has formed therein a cut-out portion which corresponds in shape to the tongue 12, and in fact is 5 formed in cutting the tongue 12 when severing the blank for the bag from the continuous strip from which it is formed. It will also be noted that that portion of the closure flap indicated by the numeral 16 has width equal to the distance between 10 the slit 11 and the top 17 of the finger opening 18.

The direct result of the arrangement just above described is that when the flap 13 is overturned on the body of the bag, the portion 16 is superimposed on the portion 19 of the side of the bag 15 carrying the tongue 12.

With the parts arranged as above described, the handle lock flap 20 is pushed through the finger opening 18 and upturned against the portion 16 holding it securely against the portion 19, 20 especially when the bag is being carried in the hand of the purchaser.

It will be noted especially, as seen in Figures 3 and 5 of the drawings, that the flap 20 is purposely constructed with slightly greater length 25 than the finger opening 18, and has formed at the ends thereof, barbs 21, the object of which is to bear against the portions of the bag below the top of the finger opening 18 to hold the flap 20 in upright or service position such as shown in Figures 30 5 and 6 of the drawings.

When the parts above described are constructed and arranged as described and shown in the accompanying drawings, it will be seen that unless the handle lock flap 20 is dislodged from engagement with the portion 16 of the closure flap 13, the closure flap cannot be opened up. At the same time it will be noted that any lateral pressure on the closure flap is counteracted by the tongue 12 which is held by and within the slit 11. The co-operation of the tongue 12 and the barbs 21 effectively prevent any accidental opening of the closure flap 13.

It will be observed by reference to Figure 1 of the drawings that the blank therein shown illustrates how the opposite ends of the blank are complementary. It also shows that in order to provide an efficient length for the exposed portion of the closure flap, the sections thereof at both sides of the slit 11 are widened with the effect, as 45 seen best in Figure 5 of the drawings, where the closure flap lies well down upon the body of the bag and serves to protect any of the contents 50 thereof in service.

To reinforce the structure just described, the 55

- blank is provided with patch sections 22 and 23. As seen in the drawings, the patch section 22 is constructed to present all of the features above described with reference to the locking members. 5 The patch section 23 in a like manner is constructed to have all of the structural features described above with reference to the disposition of the tongue 12 and finger opening 18.

In Figure 1 of the drawings, a score line 24 is 10 shown as being that on which the blank is folded in the formation of the bag. The bag shown is of the side closure type and preferably that having overturned side edges 25 which when provided with suitable adhesive, structurally close and 15 complete the bag.

While the present disclosure relates to bags of the side seam type and bags having reinforcing patches, it will be understood that I do not wish to be limited to structures embodying these features. 20

Center-seamed bags could be substituted for the side-seamed bags and both could, without altering the scope of the invention, be used with or without reinforcing patches.

25 I claim:

1. A bag as characterized having front and back portions and a closure flap extended from the front body portion of said bag, said flap having an elongated narrow central portion adapted 30 to, in conjunction with corresponding portions of said front and back, form a carrying handle for said bag, said carrying handle comprising elongated narrow sections of said front and back portions adjacent the closing bend of said flap, said 35 handle sections in said front and back being

formed by cutting elongated finger openings therein, an extension from said front portion resulting from the formation of the finger opening therein, said extension being adapted to fold through said finger openings to cover said narrow portion of said flap, a tongue formed on the opening edge of said back for engaging said front portion in holding relation thereto, and a slit formed in said front portion at the bending line 5 of said flap to receive said tongue.

2. A bag as characterized having front and back portions and a closure flap extended from the front body portion of said bag, said flap having an elongated narrow central portion adapted 10 to, in conjunction with corresponding portions of said front and back, form a carrying handle for said bag, said carrying handle comprising elongated narrow sections of said front and back portions adjacent the closing bend of said flap, said handle sections in said front and back being 15 formed by cutting elongated finger openings therein, an extension from said front portion resulting from the formation of the finger opening therein, said extension being adapted to fold through said finger openings to cover said narrow portion of said flap, a tongue formed on the opening edge of said back for engaging said front portion in holding relation thereto, and a slit formed in said front portion at the bending line 20 of said flap to receive said tongue, said tongue being cut in the bag-forming blank from the adjacent bag-forming section to shape said elongated narrow central portion of said flap.

ROBERT M. LACKEY. 35
